KILN SHELF LIFT

John P. Konkel, Webster, Mass.

Application June 21, 1955, Serial No. 36,617

Term of patent 14 years

(Cl. D81—26)

Fig. 1

I claim:

The ornamental design for a kiln shelf lift, as shown.
